PAPER WEB CONNECTING MECHANISM FOR PRINTING PRESSES

Thomas Johancen, deceased, late of Linthicum Heights, Md., by The Fidelity Trust Company, administrator, Baltimore, Md., and John Alfred Jones, Baltimore, Md.

Application April 19, 1934, Serial No. 721,358

11 Claims. (Cl. 242—58)

This invention relates to improvements in paper-web connecting mechanism for printing presses, wherein the web of a fresh roll of paper is automatically connected to the running web of an expiring roll while the press is running at high speed.

The present invention is an improvement on the structure disclosed in U. S. Patent 1,664,176 granted March 27th, 1928 to Thomas Johancen and

10 Edward Kehoe.

One object of the present invention is to provide an improved mechanism for actuating the devices that bring together the running expiring web and the web of the fresh roll and to then sever the expiring web from its core.

Another object is to provide an improved emergency tension device operating on the spindle of the running roll whereby to bring said roll to a stop in case of the breakage of the web or it becomes necessary to suddenly stop the press.

A still further object of the present invention is to provide an improved construction of belt drive to start rotation of the fresh roll to bring the same up to press speed until union of its web with that of the expiring roll has been made and to then throw out the drive for the belts and utilize the latter as a drag or tension on the running roll.

With the above, and other objects in view, the invention is illustrated in the accompanying drawings, wherein,—

Fig. 1 shows a vertical elevation of the mechanism looking toward the inner side of one of the end-frames of the press, which is of the plural deck type having arms at each deck for supporting a roll of paper.

Fig. 2 illustrates the extreme upper end of one of the end-frames to show the motor-actuated shaft for operating the vertical rack-bars.

40 Fig. 3 shows the trip devices for cutting off the motor as the rack-bars reach their limit of movement.

Fig. 4 illustrates the magnetic release for the pins that hold the lifting-arms.

45 Fig. 5 shows the end-frame of the press in side-elevation with a similar elevation of the emergency tension devices and the mechanism for actuating the devices that bring the running expiring web and the web of the fresh roll together and also the means which actuates the device which severs the expiring web from its core.

Fig. 6 illustrates a horizontal sectional detail through the parts shown in Fig. 5, as viewed on the line 6—6 thereof.

55 Fig. 7 shows a horizontal sectional detail

through the end-frame of the press as viewed on the line 7—7 of Fig. 1.

Fig. 8 illustrates, on a slightly enlarged scale, the devices viewed on the line 8—8 of Fig. 7.

Fig. 9 shows, also on a slightly enlarged scale, 5 the devices viewed on the line 9—9 of Fig. 7.

Fig. 10 illustrates a vertical sectional detail through the parts shown on the line 10—10 of Fig. 5.

Fig. 11 shows a vertical sectional elevation 10 through the parts viewed on the line 11—11 of Fig. 12.

Fig. 12 illustrates a horizontal section through the end-frame of the press, as viewed on the line 12—12 of Fig. 1.

Fig. 13 shows an enlarged view of the clutch device, which controls the belt-drive.

Fig. 14 illustrates a vertical sectional elevation showing the belt-frame and belts with the drive for the latter.

Fig. 15 shows an enlarged sectional detail of the parts of the belt-drive viewed on the line 15—15 of Fig. 14.

Fig. 16 illustrates an enlarged sectional detail through the air-cylinder which continuously 25 urges the frame in a direction to keep the belts in contact with the running roll.

Fig. 17 shows an enlarged vertical side elevation of a portion of one of the end-frames of the press together with the belt-frame, one of the vertical 30 rack-bars with the roll-lifting swinging arm and also shows the locking-bolt which normally holds the arm in position beneath one end of the roll-shaft.

Fig. 18 illustrates the locking-bolt mechanism 35 in front elevation and in engagement with the front edge of the lifting swinging arm.

Fig. 19 shows a roll of paper with its end flap prepared with paste and in readiness to be placed on one of the decks of the press, and

40 Figs. 20 to 25, inclusive, show the several positions of the running roll; belt-tension and drive; the brush and knife and the relative positions of those parts during the operation.

45 Referring to the drawings, the numeral 26 designates a vertical end bar of the press frame at the feed-end of the press, said bar frequently carrying a plurality of horizontally-extending deck-arms 27. These arms are arranged in pairs,—one bar of each pair being carried by each 50 of two of said vertical end-bars 26 and each of the pair of arms being in the same horizontal plane but each pair being located in a different horizontal plane from each of the other pairs of arms.

These pairs of arms are utilized to sustain the spindle-ends of roll-shafts 28 on which are rigidly mounted the rolls of web-paper 29 that are to be fed to the press.

5 Each of said arms 27 carries a horizontal track 30 at its inner side on which there is mounted a carriage 31 and each carriage has a bearing-block 32 in which the ends of the spindle or roll-shaft are to be seated when the rolls are first hoisted 10 in place at the outer ends of the pairs of arms.

10 Endless chains 33 are attached to the carriages and pass around sprockets 34 on a horizontal shaft 35 so that when the roll of paper is to be pushed rearwardly into running position, the carriages will travel together and deliver the two 15 ends of the spindle or shaft 28 into the seats 36 at the inner ends of the pair of arms.

15 As the spindle 28 is seated in the arm-bearings 36 it engages a lever 37 of a valve 38 (see Fig. 1) 20 and opens that valve, so as to immediately allow air, under pressure, to pass from supply pipe 39 to pipe 40, and be conducted by the latter to an air-cylinder 41 which immediately swings a belt-frame 42 toward the under side of the roll, for a 25 purpose that will presently be explained.

20 The air-cylinder 41, as best shown in Fig. 16, comprises an outer cylinder 43, closed at one end and open at the other, and an inner cylinder 44 which enters the open end of the outer cylinder 30 and has a central chamber 45 which is open to the chamber of the outer cylinder.

35 A packing 46 is placed around the open end of the inner cylinder and makes a tight joint with the inner chamber-wall of the outer cylinder 35 while the pipe 40 enters the inner cylinder and communicates with the central chamber 45 thereof, whereby air under pressure may enter said chamber 45 of the inner cylinder and pass directly into the chamber of the outer cylinder.

40 The entrance of this air tends to force the two cylinders apart and as the outer end of the inner cylinder is merely pivoted to a bracket 47 while the opposite end of the outer cylinder is attached to a swinging bracket 48, the entrance of air between the two cylinders will 45 tend to force the outer cylinder to move and swing the bracket 48. This bracket 48 is attached to a rock-shaft 49 which extends horizontally across the press from one vertical end-bar 26 to another, and said bracket carries a 50 screw-threaded rod 49 on which there is a threaded strap 50, which latter is attached to a stem 51 that projects from the closed end of the outer cylinder 43.

55 The result of these connections between the air-cylinder 41 and the bracket 48 is, that when air is admitted between the two cylinders, there is a constant tendency to turn the rock-shaft 49.

By reference to Figs. 1-14-15 and 17 of the drawings, it will be seen that a series of arms 52 are attached to the rock-shaft 49 and that each 60 of these arms is attached to one end of a belt-frame 42 which comprises a series of curved bars 53. This frame 42 therefore swings as the shaft 49 is rocked.

65 On the rock-shaft 49 there are provided a plurality of loose pulleys 54 and each pulley carries on its hub, at one side thereof, a sprocket-wheel 55.

70 The lower end of the swinging belt-frame 42 has a cross-bar 56 (see Fig. 14) on which there are carried a plurality of yieldingly mounted yokes 57 and each yoke mounts a loose pulley 58. It will be noted that there are as many yokes and 75 loose pulleys 58 as there are loose pulleys 54 on the rock-shaft 49 and the pulleys 54 and 58 are

in alignment so that flexible belts 59 may be passed around those aligned pulleys and at times be driven when the pulleys 54 are rotated by the turning of the sprockets 55, as will presently be explained.

5 By reference to Figs. 1-14 and 17, it will be noted that a cross-bar 61 extends horizontally across the belt-frame 42 and that on this bar there are mounted a plurality of idler pulleys 62' around which the back-stretch of the belts 59 pass.

10 Below the rock-shaft 49 there is located a horizontal clutch-shaft 62, one end of which (see Figs. 12-13 and 17) is carried in a bearing 63 at the left side of the press, which bearing is mounted on the rear vertical edge of the vertical end-bar 15 26 of the frame. The outer side of this bearing 63 has a cone-faced recess 64.

15 At the inner side of this bearing 63 (see Fig. 13) the clutch-shaft 62 carries a clutch-member 65 which has a sprocket-wheel 66 mounted thereon and also has a head with a conical recess 67. This clutch-member is loosely carried on the clutch-shaft 62 at the inner side of the bearing 63 and is constantly driven by a sprocket-chain 68 which passes around the sprocket-wheel 66 and 20 also passes around another sprocket 69 (see Fig. 12) that is mounted on a short stub-shaft 70 which has a bevel gear 71 that meshes with and is driven by another bevel gear 72 on a vertical shaft 73.

25 The clutch-shaft 62 carries a cone-head 74 at its outer end whose cone-surface confronts the cone-recess 64 in the outer side of the bearing 63 while at the inner side of the clutch-member 65 said clutch-shaft 62 carries another cone-head 75 which confronts the conical recess 67 in said clutch-member.

30 Bearing in mind that the clutch-member 65 revolves constantly and is normally free on the shaft 62, if cone-head 74 is moved into recess 64 40 of the bearing 63 it will hold said shaft 62 against turning, while at the same time head 75 is withdrawn from the recess 67 in the revolving clutch-member 65. If the reverse operation takes place, and head 75 is forced into recess 67 it will connect shaft 62 with the revolving clutch-member 65 while at the same time the head 74 is withdrawn from the recess 64 of the bearing.

35 The means therefore, for simultaneously moving the heads 74 and 75 will now be explained, 50 reference being made particularly to Fig. 13.

40 A bracket 76 attached to the rear vertical face of vertical end-bar 26 of the press, sustains a horizontal bar 77 while an adjustable screw-threaded rod 78 passes through a threaded supporting bracket 79 which is also attached to the vertical end-bar 26 of the press frame. Two levers 80 and 81 have their upper ends pivotally attached to the opposite ends of the upper horizontal bar 77 while lever 80 straddles the outer end of shaft 62 and engages the outer face of the cone-head 74 and lever 81 straddles the shaft 62 and engages the inner side of the head 75. The extreme lower 45 end of lever 80 engages the longitudinally-movable rod 78 near one end of the latter, while the 60 lower end of lever 81 loosely engages the other end of said movable rod 78.

45 A hand-wheel 82 is attached to the outer end of the movable threaded rod 78 by which the latter 55 may be turned.

50 Obviously, by turning the wheel 82 in one direction, the rod 78 will be drawn to the right in Fig. 13, which will swing the lower end of lever 81 toward the right and move the clutch-head 75 55 into the recess 67 of the clutch-member 65 and 75

connect shaft 62 with the rotary clutch-member and thus drive the shaft 62, while that same movement of the rod 78 to the right will swing lever 80 to the right and disengage the cone-head 5 74 from the recess 64 in the bearing. A reversal of the direction of movement of rod 74 will reverse the positions of heads 74 and 75 and thus stop shaft 62 from rotating.

When shaft 62 is engaged with the clutch, it 10 will revolve, and as this shaft carries a plurality of sprockets 83, around which sprocket-chains 84 pass, which sprocket-chains also pass around the sprockets 55 on the pulleys 54 of rock-shaft 49, those pulleys will be revolved and the belts 15 59 will be caused to travel.

When the fresh roll of paper 29 is placed in position with the spindle-ends resting in the bearings 36, the end of the spindle will engage the lever 37 of valve 38, as shown in broken lines 20 in Fig. 1, and open that valve. In Fig. 17, the roll is presumed to have just been dropped into the bearing, but the actuation of lever 37 has not yet been started.

The opening of the valve 38 allows air to pass 25 from pipe 39 to pipe 40 and from the latter into the inner cylinder 44 and build up pressure in the outer cylinder 43 against the closed inner end thereof. This pressure will push the outer cylinder lengthwise of the inner cylinder and move 30 the stem 51 of said outer cylinder upwardly so as to swing the bracket 48 and rock the shaft 49. As this shaft 49 is rocked, it will swing the lower end of the belt-frame 42 upwardly, and bring the 35 upper stretches of the belts 59 against the circumference of the roll 29.

In the meantime, the expiring roll has been lifted out of the bearing 36 and moved upwardly, while still unwinding and feeding to the press, for the purpose of vacating the bearings 36 and 40 making room for the fresh roll to be placed in the bearings.

The means for engaging the spindle-ends and lifting the expiring roll to elevate it and make room for the fresh roll, are substantially like 45 those employed in the Johancen-Kehoe Patent 1,664,176 hereinbefore referred to, and a brief description thereof is believed to be sufficient.

At the inner side of each vertical end-bar 26 of the press frame there is provided a vertical 50 rack-bar 85 which extends from a point below the lowermost deck-arms to a point above the uppermost pair of said deck-arms. The vertical movement of the rack-bars is the equivalent of the distance from the bearing 36 upward to the 55 point where the expiring roll is to be lifted.

The lifting of the rack-bars 85 is effected through a motor-driven vertical shaft 86 (see Figs. 1-2 and 7) carrying a worm 87 near its lower end, which worm meshes with a worm-wheel 88 on a horizontal shaft 89. On this same horizontal shaft 89 are two gears 90,—one at each end thereof, and these gears mesh with and drive interposed idler gears 91 which latter engage the racks on the edges of rack-bars 85.

The upper end of the vertical shaft 86 carries a gear 92 (see Fig. 2) which meshes with and is driven by a pinion 93 on the shaft of a reversible motor 94 so that when the motor is operated it will drive vertical shaft 86 and through the gearing at the lower end of said vertical shaft, the racks will be moved up or down vertically.

The means for stopping the motor when the racks have reached their limit of up or down movement, is disclosed in Figs. 2 and 3, wherein, 75 a vertical arm 95 is shown as projecting from

the upper end of the rack-bar, and this arm carries two trip devices 96 and 97. When the motor has been started, the rack will move upwardly, and continue to so move, until the trip device 96 strikes a snap-switch 98, whereupon the motor 5 will be stopped.

When the return movement is made, the trip 97 will strike another snap-switch 99 and again stop the motor.

Each rack-bar 85 is provided with a plurality 10 of pivoted lifting arms 100,—one above the other and adjacent each of the decks. These arms are pivotally connected at their lower ends to the two rack-bars so they may operate in pairs, that is, 15 one arm on one rack-bar cooperates with a like arm on the other rack-bar to form a pair of arms. Each pair of said arms 100 have bearing recesses 101 in their upper free ends, as shown in Figs. 4 and 17, for engaging, when swung outwardly, under the opposite ends of a spindle 28 on which 20 the exhausting roll is mounted.

A roller 102 is carried at the upper free end of each swinging arm and this roller, when the arm is released and its upper end swings outwardly, will engage and ride on the upper edge of an inclined bar 103 and thus guide the spindle 28 and the expiring roll 29 as the latter is raised for the purpose of making room in the bearing 36 for the spindle of the fresh roll.

When a fresh roll has been started and its web 30 fed through the press, the rack-bars 85 will be in their lowered positions and the swinging arms 100 will be swung back where they are held by means of latch-bolts 104 which are shown in Figs. 4-17 and 18.

These latch-bolts are attached to the front edge of the vertical end-bars 26 of the press frame and are released by energizing electromagnets 105 which actuate armature-release levers 106.

Spring plates 107 yieldingly bear against the rear edges of the swinging arms 100 and when the bolts 104 are retracted, these spring plates push the arms forwardly until the rollers 102 engage the edges of the inclined guide bars 103, 45 at which time the recesses 101 in the upper ends of the arms have position immediately below the spindle-ends as shown in Fig. 17.

Presuming now, that the running roll is nearing exhaustion and the same has been elevated 50 by the lifting arms and racks into the position shown in Fig. 1, and a fresh roll has been positioned on the deck beneath the raised running roll.

This fresh roll has previously been prepared in 55 that the under side of its flap 108 has been secured down by the application of paste 109 at spaced intervals and at points set back from the marginal edge of the flap.

To the outer side of the flap 108, also at spaced 60 intervals there are applied coatings of a cement 110 of greater tenacity than the paste 109 at the under side of the flap. These applications of cement 110 are nearer the marginal edge of the flap than the paste applications at the under side. 65

The spaces 111 between the cement applications at the outer side of the flap are provided so that when the roll is contacted by the belts 59, which latter are first caused to travel so as to revolve the roll up to press speed, the belts will engage 70 the roll at said spaces and between the cement applications so that cement will not be transferred to those belts.

After the joint of the new roll web with that of the expiring roll web, the belts will be stopped 75

and will thereafter act as a drag on the running roll so as to serve as a tension and prevent the roll from turning faster than press speed.

When the elevated exhausting roll has been reduced in size to a point where it is desired to connect that web with the web of the fresh roll, the next step is to start the revolution of the fresh roll by driving the belts 59.

In the present instance, this is effected by actuating the clutch 75 so as to begin driving shaft 62 and the shaft 49 so as to drive the belts. The belts then being in contact with the fresh roll will drive the latter until it is up to press speed.

The next step is to bring the running expiring web into contact with the cement-coated flap 108 of the fresh revolving roll. This is effected by means which will now be explained, reference being made particularly to Figs. 5-6-7-8-9-10 and 11.

On one end of each spindle 28 there is a grooved circular head 112 at whose inner side there is provided a cam 113. The cam therefore revolves with the web roll, and, as shown in Fig. 10, has position at the outer side of the deck-arms 27 in which the bearing 36 for the spindle is formed.

At the front forward edge of the vertical end bar 26 of the press frame there is sustained a vertical bar 114 whose lower end is square in cross-section so that the same will be held in its guide brackets 115 against turning. To the lower end of this vertical bar 114 there is attached a bracket 116 which carries a solenoid 117. This solenoid has a core on one end of which there is a circular head 118 so that when the solenoid is energized the head 118 will be projected outwardly in the path of the cam 113 on the head.

As the solenoid and its head are both carried on the bracket 116 and the latter is attached to the lower end of the vertical bar 114, when the head 118 is projected in the path of the cam 113 it will be engaged by that cam and pushed downwardly as the cam turns, thus depressing the vertical bar 114.

The vertical bar 114 (see Fig. 5) is surrounded by a coiled spring 119 which normally holds the bar up, but which will compress when the bar is moved down.

The upper end of the vertical bar 114 carries a bracket-plate 120 which has a horizontal trip-portion 121 and a vertical portion whose lower end carries a yielding trip-finger 122.

Below the trip-finger 122 there is a horizontal brush-shaft 123 which extends across the press between the deck-arms 27, and one end of this shaft carries a lever-arm 124 which latter is provided with a slot 125 through which the vertical bar 114 extends. A semicircular loose head 126 is carried on the vertical bar 114 and this head seats against the upper side of the lever-arm 124 around the slot, while a coiled spring 127 encircles the bar and has its lower end seated on the upper side of the same circular head 126. The upper end of said spring seats beneath the bracket plate 120. The spring 127 therefore exerts a constant downward push on the loose head 126 and tends to swing the lever-arm 124 downwardly.

The outer free end of the lever-arm 124 is provided with a laterally-projecting hand lug 128 and this lug, when the bar 114 is raised, is engaged by the lower hook-end 129 of a depending lever 130 and thereby held up against the action of the spring 127 and thus holds the brush-shaft 123 against turning.

The depending lever 130 is pivoted at 131 to the side of the vertical bar 26 of the press frame, and just above this pivot, said lever is formed with a cam face 132 at one side thereof and just beneath the trip-portion 121 of the bracket-plate 120 that moves with the vertical bar 114.

Thus it will be seen that when the vertical bar 114 is depressed by the cam 113 engaging the head 118 of the solenoid, the trip portion 121 of the bracket-plate will engage the cam face 132 at the upper end of the depending lever and swing the hook-end 129 from beneath the hand-lug 128 of the lever-arm 124 and allow the spring 127 to depress said arm thereby causing the brush-shaft 123 to be rocked.

On the brush-shaft 123 there are two spaced apart arms 133 the swinging ends of which sustain between them a web depressing device, which in this instance is a brush 134. This brush extends horizontally across the press, directly over the running web 135 of the expiring roll, and also over the fresh roll which has been put in place, as shown in Figs. 1-23-24 and 25. It will be noted that the running web is guided in its travel by idler rolls 136 and 137 and the web-depressing device is located in front of idler roll 136.

From the above explanation, it will be understood that when solenoid 117 is energized, such as by closing a circuit at push-button switch 138 (see Fig. 5) the head 118 on the solenoid-core 30 will move outwardly and be engaged by the cam 113 on the side of the spindle-head 112, whereupon, vertical bar 114 will be depressed, latch 130 will release lever-arm 124 and allow brush-shaft 123 to rock. As shaft 123 rocks, arms 133, carrying the web-depressing device, in this case the brush 134, will swing down and lower the brush against the upper side of the traveling exhausting web 135, thereby depressing the latter into contact with the revolving fresh roll, as shown in Fig. 24, so that when the cement-coated flap 108 of the fresh roll passes under the brush said flap will be cemented to the running web and be carried forward with the latter into the press.

The only remaining thing to be done to complete the union of the fresh web with that of the expiring web is to sever the running web from the expiring core, and this will now be explained.

By reference to Fig. 5, it will be noted that the push-button switch 138 is provided with a trip-finger 139 which latter is pivoted thereto in such manner that it may be swung up from its pivot 140. A lug 141, formed integrally with the trip-finger, strikes against the rear face of the bracket-arm 142 which limits the downward swing of said trip-finger.

Depending from the box of the push-button switch is a stem 143 which is movable upwardly from the position shown in Fig. 5, to cut off the circuit that is formed when the button 138 is pushed in and the lower end of this stem, when the circuit has been closed, terminates just over the free end of the trip-finger 139.

On the vertical bar 114 there is carried a laterally-projecting arm 144 with a trip-pawl 145 at its projecting end.

The position of the pawl 145 with respect to the end of the trip-finger 139 is such that when the vertical bar 114 is depressed, carrying the arm 144 and pawl 145 with it, the pawl 145 will strike the end of the trip-finger when passing downwardly, but as the pawl 145 is pivoted to the arm, it will simply swing up and pass over said trip-finger end.

On the return, or up stroke of the vertical bar 75

114 however, the pawl 145 will engage under the free end of the trip-finger and lift the latter so as to cause it to swing up under the stem 143 and move the latter up. This upward movement of the stem 143 will break the circuit to the solenoid 117 and allow the head 118 to withdraw from the path of the cam 113.

When the vertical bar 114 is depressed, coiled spring 119 is compressed so that when the cam 113 rides off from the head 118 the vertical bar will at once begin its return or up stroke. During this up-stroke, pawl 145 actuates trip-finger 139 and stem 143 and cuts off the current to the solenoid 117 and retracts the core and the head 118.

Another operation results upon the return or up stroke of the vertical bar 114, and that is the tripping of the cutter-blade 146. This is effected by means which will now be explained, reference being made particularly to Figs. 5-7-8-9 and 14.

A short horizontal shaft 147 is sustained in suitable brackets 148 and the outer end of this shaft is provided with a tripping-head 149. When the vertical bar 114 is in the elevated position, as shown in Fig. 5, the tripping-head 149 is slightly below, but in the path of the yielding trip-finger 122 which latter is carried at the lower end of the vertically-movable bracket-plate 120.

As the bar 114 moves downwardly, this tripping-finger 122 will yield as it passes over and under the tripping-head 149 on the outer end of the shaft 147, but when the bar 114 returns, said tripping-finger 122 will engage under the tripping-head 149 and swing the same upwardly, thereby rocking the shaft 147.

Near the inner end, shaft 147 carries a short crank-head 150 whose lower free end is pivotally attached to the rear end of a substantially horizontal connecting bar 151, while the forward end of this connecting bar 151 is pivotally engaged with the free end of a swinging arm 152 which latter projects from the side of a circular drum 153 which is carried on one end of a knife-shaft 154. This knife-shaft 154 extends horizontally across the press and is sustained in horizontal bracket-arms 155 which extend forwardly from the brackets 148.

It is to the shaft 154 that the knife or cutter-blade 146 is attached, so that as the shaft 147 is rocked by the up-stroke of the tripping-finger 122, the crank-head 150 will be swung downwardly and toward the rear, thus pulling connecting bar 151 rearwardly and swinging arm 152 so as to rock the knife-shaft 154 and thereby swing the cutting edge of the knife downwardly against the running expiring web 135 and severing the latter just forward of the joint of the flap 108 of the fresh roll to the running expiring roll, as shown in Fig. 25.

The circular drum 153 contains a coiled spring 156 (see Fig. 9) which serves to return the knife-shaft and knife to the normal position, a stop pin 157 serving to limit such return movement.

In order to promptly stop rotation of the running roll 29 and the spindle 28 on which the same is mounted, in case of breakage of the running web, or for any other reason, there is provided an emergency brake to coat with the circular head 112 which latter is permanently attached to one end of said spindle.

This mechanism therefore, now to be explained, is best illustrated in Fig. 5.

Carried at the outer side of the vertical end bar 26 of the press frame is a vertical bracket 158 having upper and lower horizontal pins 159 and 160 respectively.

On the lower pin 160 there is mounted a head 161 having an arm 162 extending rearwardly therefrom which latter pivotally connects to the lower end of a core 163 of a solenoid 164. The wires connecting this solenoid include in their circuit a push-button switch (not shown) but commonly located within ready reach of an attendant at the control station, and usually termed the red button.

At one side of the head 161 there is a second head 165 which has a cam face 166 across its upper side.

From the second head 165 there extends a lower lever 167 which projects forwardly under the grooved head 112. The forward end of this lever 167 pivotally engages the lower end of an adjustable hook-bar 168,—the upper end of which bar carries a hook 169 which detachably connects with a pin or lug 170 that projects from the forward end of an upper lever 171. The rear end of this upper lever is pivotally connected to the upper horizontal pin 159 of the vertical bracket 158.

This upper lever 171 pivotally carries a brake-shoe 172 which fits into the groove of the circular head 112 that is carried on the end of the roll spindle 28.

To the lower lever 167 there is pivotally connected the forward end of a supplemental lever bar 173 while the rear end 174 of this bar seats on the cam face 166 of the head 165.

A brake-shoe 175 is pivotally connected to the supplemental lever bar 173 which shoe enters the lower portion of the groove of the circular head 112.

From the above explanation it is believed to be clear that when the so-called red button is pushed, a circuit will be closed through the solenoid 164 and core 163 thereof will be drawn upwardly, thereby lifting the outer end of arm 162 and rocking heads 161 and 165. As these heads are rocked, the forward end of lower lever 167 will be swung down, pulling hook-bar 168 down with it, and thereby drawing down on the forward end of upper lever 171 and seating the upper brake-shoe 172 in the groove of spindle head 112.

As the forward end of lower lever 167 swings down, it also draws down on the forward end of supplemental lever 173, while the turning of the cam face 166 on the head 165 will swing the rear end 174 of said lever 173 upwardly and thereby press the lower shoe 175 into the groove of spindle head 112.

Thus the movement of the solenoid core 163 will clamp the circular head 112 between the two brake shoes 172 and 175 and by frictional contact therewith will stop rotation of the head 112, the spindle 28 and the roll 29 mounted thereon.

Having described the invention, what is claimed is,—

1. In a paper feeding device for printing presses the combination with means for normally sustaining a rolled web of paper while the latter is being fed to the press, of a pair of arms for lifting the expiring running roll from the normal sustaining means to make room for a fresh roll of paper, an inclined guide for directing the movement of said arms, pins for holding said arms in their normal folded positions and means for electrically releasing the pins to free the arms when the expiring roll is to be lifted.

2. In a paper feeding device for printing presses the combination with means for normally sustaining a rolled web of paper while the latter

is being fed to the press, of means for lifting the expiring running roll from the normal sustaining means to make room for a fresh roll of paper, a swinging belt-frame carrying a plurality of 5 belts to engage the fresh roll, fluid-actuated means for moving the belt-frame to bring the belts into contact with the fresh roll, a valve to control the fluid to said fluid-actuated means and means coacting with the valve and automatically operated upon placing the fresh roll in 10 position to open the valve and allow fluid pressure to actuate said frame.

3. In a paper feeding device for printing presses the combination with means for sustaining an expiring roll of paper while the latter is being fed to the press, of means for sustaining a fresh roll of paper, means for revolving the 15 fresh roll, a device for bringing the web of the expiring roll and the periphery of the revolving 20 fresh roll together, means revolving with the fresh roll and a solenoid-actuated device coacting with said revolving means for operating the device that brings the expiring web and the fresh roll together.

25 4. In a paper feeding device for printing presses the combination with means for sustaining an expiring roll of paper while the latter is being fed to the press, of means for sustaining a fresh roll of paper, means for revolving said 30 fresh roll, a device for bringing the web of the expiring roll and the periphery of the fresh roll together, a cutter for severing the expiring web, reciprocating means which when moved in one direction will actuate the web-bringing-together 35 device and when moved in the other direction will actuate the cutter and electrically-controlled means for actuating the reciprocating means.

5. In a paper feeding device for printing 40 presses the combination with means for sustaining an expiring roll of paper while the latter is being fed to the press, of means for sustaining a fresh roll of paper, means for revolving said fresh 45 roll, a rock-shaft carrying a device for bringing the web of the expiring roll against the periphery of the fresh revolving roll, a cutter for severing the expiring web, a reciprocating bar, means actuated by said bar for rocking said shaft, means also actuated by said bar for operating the cutter and means rotating with the fresh 50 roll for operating the bar.

6. In a paper feeding device for printing presses the combination with means for sustaining an expiring roll of paper while the latter is being fed to the press, of means for sustaining a 55 fresh roll of paper, means for revolving said fresh roll, a rock-shaft carrying a device for bringing the web of the expiring roll against the periphery of the fresh revolving roll, a cutter for severing the expiring web, a reciprocating bar, 60 means actuated by said bar for rocking said shaft, means also actuated by said bar for operating the cutter, a cam-device rotating with the fresh roll, a device carried by the reciprocating bar and projectable into the path of said cam-device and means for electrically controlling 65 said projectable device.

7. In a paper feeding device for printing 70 presses the combination with means for sustaining an expiring roll of paper while the latter is being fed to the press, of means for sustaining a fresh roll of paper, means for revolving said fresh roll, a reciprocating bar, a cam-device rotating with one of the rolls, a solenoid-controlled head carried from said bar and normally 75 held out of the path of the said cam-device,

means actuated when the bar moves in one direction for bringing the web of the expiring roll and the web of the fresh roll together and electric means for controlling the solenoid.

8. In a paper feeding device for printing 5 presses the combination with means for sustaining an expiring roll of paper while the latter is being fed to the press, of means for sustaining a fresh roll of paper, means for revolving said fresh roll, a rock-shaft carrying a device for bringing the web of the expiring roll against the periphery of the fresh revolving roll, a cutter for severing the expiring web, a reciprocating bar, means actuated by said bar for rocking said shaft, means also actuated by said bar for operating the cutter, a solenoid sustained from said bar said solenoid having a movable head, a cam rotating with the fresh roll and normally clearing said head, electric connections including a switch for controlling said solenoid and means carried by said bar for opening said switch when the bar moves in one direction.

10 9. In a paper feeding device for printing 15 presses the combination with means for sustaining an expiring roll of paper while the latter is being fed to the press, of means for sustaining a fresh roll, a rock-shaft carrying a device for bringing the web of the expiring roll against the periphery of the fresh revolving roll, a cutter for severing the expiring web, a reciprocating bar, a solenoid sustained from said bar and having a movable head, a cam rotating with the fresh roll, electric connections including a switch for controlling said solenoid and means carried by said bar for opening said switch when the bar moves in one direction.

20 30 35

10. In a paper feeding device for printing 40 presses the combination with means for sustaining an expiring roll of paper while the latter is being fed to the press, of means for sustaining a 45 fresh roll, a cam revolving with the spindle of the fresh roll, a bar sustained so as to be reciprocated, a bracket carried by said bar, a solenoid carried by said bracket and having a movable head which is normally close to but out of the path of said cam, spring means for normally holding the bar in one position, a rock-shaft carrying a device for bringing the web of the expiring roll into contact with the periphery of the fresh roll, electrical connections for controlling the solenoid to project the head in the path of said cam and move the bar in one direction, a latch device for holding the rock-shaft against movement, means movable with the bar for releasing the latch device, a cutter for severing the expiring web and means coacting between the bar and cutter for actuating the latter after the shaft has been 50 rocked by the release of the latch device.

55 60 65 70 75

11. In a paper feeding device for printing presses the combination with means for sustaining a spindle on which is mounted a rolled web of paper while the latter is being fed to the press, of a head on the spindle, a bracket sustained adjacent to said head, a lever pivotally connected at one end to said bracket and extending across the face of the head at one side thereof, a brake-shoe carried by said lever, an-

other lever having one end pivotally connected to said bracket and extending across the face of the head at the diametrically-opposite side thereof, a link-bar detachably connecting the 5 other ends of said two levers, a supplemental lever-bar attached to one of said levers and carrying a brake-shoe and a solenoid-operated arm for operating said levers to draw the shoes against the said head.
